(57) **CLAIM**

The ornamental design for a docking station as shown and described.

DESCRIPTION

FIG. 1 is a front, left and top perspective view of a docking station showing my design;

FIG. 2 is a rear, right and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is an enlarged view of portion 9 shown in FIG. 5; and,

FIG. 10 is an enlarged view of portion 10 shown in FIG. 6.

The dash dot broken lines in the figures depict reference to the enlargements shown in the figures and form no part of the claim. All other broken line depict portions of the docking station that form no part of the claimed design.

1 Claim, 10 Drawing Sheets
